Paul H. Moore & Sonnenfeld.

UNITED STATES PATENT OFFICE.

CHARLES A. MOSGROVE, OF WATERTOWN, CONNECTICUT, ASSIGNOR TO THE AUTOYRE COMPANY, A CORPORATION OF CONNECTICUT.

DESIGN FOR A TUMBLER-HOLDER.

57,989.

Specification for Design.

Patented May 24, 1921.

Application filed December 11, 1920. Serial No. 430,060. Term of patent 14 years.

To all whom it may concern:

Be it known that I, CHARLES A. MOSGROVE, a citizen of the United States, residing at Watertown, county of Litchfield, State of Connecticut, have invented a new, original, and ornamental Design for a Tumbler-Holder, of which the following is a specification, reference being had to the accompanying drawing, forming part thereof.

The figure is a view in perspective of a tumbler holder showing my new design.

I claim:

The ornamental design for a tumbler holder, as shown.

CHARLES A. MOSGROVE.

Witnesses:

R. K. STEWART,
H. W. CALKINS.
